UNITED STATES PATENT OFFICE.

JOHN J. WALTERHOUSE, OF VINCENNES, INDIANA.

CENTRIFUGAL REEL.

SPECIFICATION forming part of Letters Patent No. 274,234, dated March 20, 1883.

Application filed November 3, 1882. (No model.)

To all whom it may concern:

Be it known that I, JOHN J. WALTERHOUSE, of Vincennes, in the county of Knox and State of Indiana, have invented certain Improvements in Centrifugal Reels, of which the following is a specification.

My invention relates to that class of machines employed in milling commonly known as "centrifugal reels;" and it consists in various features hereinafter explained.

In the accompanying drawings, Figure 1 represents a longitudinal central section through my improved machine; Fig. 2, a vertical transverse section of the same; Fig. 3, an end view of the reel-head; Fig. 4, a side elevation of the same; Fig. 5, a side or face elevation of the beater-cylinder with a few of the blades or flights in position; Figs. 6 and 7, plan and end views of the hanger or bracket which carries or supports one end of the beater-shaft.

The general principle and mode of operation of my machine are essentially the same as in other machines of this class—that is to say, the material enters a reel or cylinder covered with bolting-cloth or screening material and arranged to revolve slowly, the finer material being caused to pass through the meshes of the reel cloth or clothing by the action of a rapidly-rotating internal beater or fan-like cylinder, the offal or coarser matters passing off at the tail of the reel.

My improvements are designed to render the machine more perfect in its action, to simplify its construction, and to enable the operator to keep it always in perfect working condition without difficulty or inconvenience. With these objects in view I construct my machine as represented in the drawings, in which—

40 A represents a stout frame, ordinarily made of wood; B, the reel or cylinder arranged in said frame; and C, the beater, likewise mounted in the frame and arranged within the reel, as shown. The reel or cylinder B is provided 45 with tubular journals *a b* of sufficient size to permit the shaft D of beater C to pass freely through them without actual contact, so that there shall be no friction of one upon the other and no tendency of one to be influenced by the 50 other in its rotation. The journal *b* is made of greater diameter than journal *a*, in order that room may be afforded for a spiral feeding

blade or worm, *c*, secured upon the shaft D and passing through the journal *b* into the feed-box *d*, which is fixed to the framing A. 55 The journals *a* and *b* are mounted in laterally-adjustable boxes or bearings E, which rest and are arranged to slide a limited distance upon supporting frames or brackets F G at opposite ends of frame A, set-screws *e* and jam-nuts *f* being provided to effect and maintain the adjustment of the journals of the reel. In like manner the ends of shaft D are carried in laterally-adjustable boxes or bearings H, also arranged to slide a short distance upon the 65 supporting frames or brackets F G, and likewise provided with adjusting-screws *g* and jam-nuts *h*. By means of the adjustable boxes or bearings E and H the shaft D may be accurately centered in the tubular journals *a b* 70 of the reel, and consequently the beater will be exactly centered in the reel—a feature of great importance, and very essential to the success of this class of machines.

The beater C is composed of the central 75 shaft, D, a series of spider heads or frames, I, and a series of longitudinal blades or flights, *i*, secured to the annular rims of the spider-frames, as more plainly seen in Fig. 5.

Heretofore the blades have been made of 80 one continuous strip each, involving the necessity of an entire new blade in case of injury, and also requiring long and comparatively expensive strips of material in the first instance. I however employ at suitable intervals heads 85 having wide flanges or ears to permit the attachment to one head of the ends of independent blade-sections, thus permitting shorter sections to be used.

The heads or spider-frames are made adjustable upon the shaft, being held by set-screws *j*, or equivalent means, so that they may be rotated upon or moved lengthwise of the shaft, as desired. This facility of adjustment permits the heads or spider-frames to be set 95 differently upon their shaft, and allows the blades to be set at any desired angle to the shaft. It also permits one blade-section to be set at a greater or less angle or inclination relatively to the shaft D than another section, 100 thus enabling the builder or the operator to give the blades one inclination through one part of the length of the beater and another or other inclinations at a different part or parts

in its length, as may be required or advantageous with different grades of bolting-cloth commonly used on different portions of the reel or cylinder, or by different conditions of the material in different parts of the reel. It will be seen that even with continuous blades or flights some variation in the inclination can be readily made.

It is desirable that the ends of the separate sections should abut against one another and form in effect a continuous blade, for the reason that any open space between the ends will cause eddies and currents of air that will in some degree interfere with the perfect separation of the material into distinct grades. While, therefore, the machine will be operative, even if the blade-sections do not abut, it is preferable to have them do so.

The bolting reel or cylinder consists of two heads, J K, each formed or furnished with a tubular shaft, lettered respectively *a* and *b*, as above mentioned, said heads being connected and tied together by longitudinal ribs or rods *k*, bolted or screwed to the heads, as shown in Fig. 1. The head J is encircled by an annular band, L, formed with an inwardly-projecting radial flange, or lugs, *l*, which overhang the head, as shown in Fig. 1. This band fits snugly around the head J, but is free to slide or move thereon in the direction of the length of the reel; and for the purpose of moving it outward or away from the head, cams or circular wedges *M* are journaled upon the head J by central pivot bolts or screws, *m*, so that by rotating said cams or wedges the band L will be drawn outward.

In order to provide for the more convenient turning of the cams, and for the gradual and accurate adjustment thereof, their peripheries are toothed and caused to mesh with small pinions *n*, each turning upon a stud or center pin, *o*, fast to the head J. The pinions are each furnished with a squared head or neck, *p*, to receive a wrench or other tool by which to turn them.

N N represent two flexible bands, preferably of hoop-iron or like material, one encircling the head K and the other encircling the band L, and each formed or provided with ears *q* near its end, and with a right-and-left screw-stem, *u*, screwing into said ears and serving to draw them together, the middle portion of the stem being squared for convenience in turning. These bands are for the purpose of clamping and holding the bolting-cloth upon the reel at the ends, and, if necessary, similar bands may be applied at intermediate points in the length of the reel, being placed directly around the inner stiffening ribs or hoops *r*. Ordinarily, however, the bands will be used only at the ends, and the intermediate portion of the reel-clothing, being left free, can be drawn tight by the rotation of the cams *M* and the consequent outward movement of ring or band L, and with it the band N thereon. If intermediate retaining-bands N be employed,

they should be loosened when the cloth is to be tightened. The cloth may be laced along the seam or otherwise secured, as found expedient.

The body of the machine is boarded or closed, as usual, and beneath the reel or bolting-cylinder the sides of the chest are inclined toward each other, as more plainly seen in Fig. 2. The inclined sides are composed of or provided with numerous slides or movable boards, O, each capable of being raised and lowered independently of the others. Directly beneath the line of meeting of the two inclined sides or series of boards O is placed a vertical board, P, which forms a partition between two conveyer-troughs, Q, each furnished with a conveyer, R. By opening a part of the slides on one side and another portion, not opposite to the first, on the opposite side, it will be seen that the material will fall partially into one trough and partially into the other. The point of division may be regulated by opening or closing the slides O, so as to cause material of one grade to pass wholly into one trough and that of another or different grade to pass to the other trough, whence they may be delivered to different points.

For the purpose of imparting motion to the apparatus, I secure upon the shaft D a driving pulley, S, which receives motion from any prime motor by belt. Said shaft is further provided with a belt or chain wheel, T, from which motion is transmitted through a belt or chain, *s*, to a larger wheel, U, on one of the conveyer-shafts R. A second wheel, V, on said shaft gives motion to the reel or cylinder B through a belt or chain, W, and a wheel, X, secured upon the reel-journal *a*, as shown. The second conveyer may be turned by a belt from shaft D, or by belt or gear from the first conveyer-shaft.

In order to bring the wheels V and X close up to the frame, the bracket or supporting-frame F is curved outward and made of semi-circular form, as shown in Fig. 6, and both this bracket and the bracket or frame G are supported and braced by rods *t*, extending drum to and bearing upon the frame A.

The bolting-cloth may be either of silk or wire, or of other suitable material.

The varying inclination of the blades causes the material to be moved more rapidly through the reel at one point than at another, and also varies the force with which the blades act.

For the purpose of holding the slides O in their elevated position, I provide spring arms or holders Y, as shown in Fig. 2, which bear against the slides with sufficient force to retain them in said position.

Having thus described my invention, what I claim is—

1. In a centrifugal reel substantially such as described, the combination of a reel provided with journals at its ends, and laterally-adjustable boxes or bearings adapted to receive and support said journals.

2. In a centrifugal reel, the combination of

a reel, a beater or cylinder arranged within said reel, and laterally-adjustable boxes or bearings for the journals of the reel and beater, all arranged substantially as described and shown, whereby the beater may be accurately centered within the reel.

3. In a flour-dressing machine substantially such as described, a beater having its blades made in independent longitudinal sections, the sections of each blade being directly in line with and abutting against one another and forming a continuous blade, whereby the different sections are adapted to be adjusted at varying inclinations without destroying the continuity of the blades.

4. In a flour-dressing machine substantially such as described, a horizontal rotary beater having blades forming continuous lines from end to end, said blades having a varying inclination relatively to the axis of the beater at different parts of their length, substantially as and for the purpose specified.

5. In a flour-dressing machine substantially such as described, a beater having its blades made in independent longitudinal sections, whereby they are adapted to be renewed in part without renewing the whole.

6. A beater-cylinder for flour-dressing machines, provided with blades inclined in relation to the central axis of the cylinder, and having a greater inclination at one part of their length than at another, substantially as and for the purpose set forth.

7. In combination with a reel having cloth or clothing of different grades, an internal beater having its blades set at varying inclinations at different points in their length to correspond with the variations in the cloth.

8. In combination with the reel B and band L, a series of circular cams or wedges mounted upon studs or pivots on the head and adapted to move the band outward, substantially as set forth.

9. In combination with reel B, band L, circular wedges M, having toothed peripheries, and pinions *n*, meshing therewith, said parts being arranged to operate substantially as described.
